UNITED STATES PATENT OFFICE

FRIEDRICH CLAUS HEINRICH HANSEN, OF HAMBURG, GERMANY, ASSIGNOR TO NIER & EHMER, OF BEIERFELD, GERMANY

COIN FREED AUTOMATIC SHOOTING MACHINE

Original application filed June 26, 1929, Serial No. 373,844, and in Germany February 27, 1929. Divided and this application filed May 29, 1930. Serial No. 457,315.

This is a division of application Ser. No. 373,844 of June 26, 1929.

This invention relates to an electrically operated, cinematographic shooting machine comprising a mechanism, controlled by a rifle, for piercing a diapositive in the form of a miniature target against a projected image of which the rifle is aimed, and the invention consists in the combination with an operating magnet for said target piercing mechanism, of a coin-operated switch, and a two-way switch adapted to cooperate with the coin-operated switch for effecting a partial closure of the circuit of said magnet when a loading mechanism in the rifle is operated, and to complete the circuit when the trigger is pulled.

10

Fig. 1 of the accompanying drawings represents a view of the coin slot and of the 20 switch operated by the coin,

Figs. 2 and 3 are views of further switches employed in the machine, and

Fig. 4 is a diagram of the electric connections.

25 The automatic shooting machine to which the invention relates comprises a dummy rifle, an optical projection apparatus whereby an enlarged image of a miniature target is projected on a wall or screen, a device whereby the target is pierced so as to produce a corresponding effect on the image at the exact spot towards which the rifle is aimed at the moment of firing the shot, and a coin-freed device whereby, in conjunction with a loading mechanism in the rifle, the piercing device is prepared for operation, all these elements and the manner in which they are combined being described in the specification of Patent No. 1,819,954. The loading mechanism, 40 which is retained in tensioned position by the trigger and released when the latter is pulled, displaces a rod 19 (Fig. 3) the lower end of which bears against a lug 21 on a lever 23 mounted on a pivot 22. A compression spring 45 27 bears against another lug on the lever, and against a lug 28 on a rigid bracket 29 secured to the rifle carrier 20 wherein the rod 19 is guided. The spring thus supports the rod 19 and opposes the operation of the loading mechanism. The switch arm 24 of a two-way

switch B is mounted on the same pivot as the lever 23 and moves between two electric contacts 30 and 31. A spring 25 connects the arm 24 with the lever 23 at a point which passes the dead centre position and therefore causes the arm to spring over from one contact to the other on the lever being rocked.

The switch lever 24 normally engages the contact 31. When the loading mechanism is tensioned the lever springs over to the contact 30, and when the mechanism is released by the pulling of the trigger, the lever springs back to the contact 31.

The piercing mechanism whereby the target is perforated comprises a piercing needle 51 (Fig. 4) carried by a pivoted hammer 52. The latter is operated by a magnet H through the medium of a rocking lever which, on being rocked by the magnet for operating the hammer, actuates the contact springs 71 of a switch C for closing the latter, as described in the parent specification.

The operation of the machine is dependent on the insertion of a coin in a slot 117 (Fig. 1) which leads through chutes 115 and 120 into a suitably arranged collecting box. The inserted coin 118 is retained at the end of the chute 115 by a stop 119, as shown in Fig. 1. The stop 119 is seated upon a lever 122 which is adapted to rock about a pivot 121 and which is provided at its free end with the three cornered head 123. A spring 124 controls the lever and maintains the stop 119 in operative position.

By means of a hand lever 126 which is pivoted at 125, adjacent the coin slot 117, the coin 118 can be driven forcibly into the coin chute 120. The hand lever 126 is for this purpose linked by the arm 127 to a longitudinally guided slide 128 which, upon the lever being operated, strikes against the coin 118 and forces it past the beveled end of the stop. A tension spring 129 restores the hand lever 126 to the starting position after being set free.

Under the pressure of the slide 128 against the coin the stop 119 yields and turns the lever 122 in opposition to the spring 124. Upon this movement of the lever a bell-crank 131, arranged on a pivot 130 with one arm in

the path of the three cornered lever head 123 and with the other arm 132 in the coin slot 117, is turned by the head, in opposition to a spring 133, into a position wherein it blocks 5 the coin slot. The lever is locked in the operated position by a catch 136 which rocks about a pivot 135 under the action of a spring 137 and which places a nose piece 138 under the head 123 so as to prevent the lever from returning. The return of the levers into the position wherein the coin slot is free is dependent upon the excitation of an electro-magnet G, whose armature is coupled through 10 a link 134 with the catch 136.

15 The catch 136 carries a switch arm 139 which co-operates with contacts 140 in a switch A and which closes a circuit under the influence of the spring 137 and breaks it under the influence of the magnet G. Fig. 1 20 shows the elements in the normal position, i. e. with the coin slot free and with the circuit at A broken.

In the arrangement shown in the drawings the coin-free device is adapted to allow two 25 operations of the rifle after each insertion of a coin. For this purpose the electro-magnet G will not come into operation for clearing the coin-slot until two shots have been fired, the insertion of coins in the slot being prevented 30 in the meantime.

The circuit whereby the excitation of the electro-magnet G is carried out contains a switch roller 142 rotatable about a shaft 141. At each use of the rifle the roller experiences 35 a partial rotation, but effects the circuit closure only at every other partial rotation. To the switch roller 142 is connected a ratchet wheel 143 in which engages a spring controlled ratchet pawl 144 mounted upon a 40 crank-arm 145 which rocks about the shaft 141. The crank arm is operatively connected by means of the link 146 with a switch lever 148 mounted on a pivot 147. The switch lever 148 is connected by a link 149 to the armature 45 of an electro-magnet L, upon the excitation of which it is turned, against the tension of a spring 150, into engagement with contacts 151 in a switch D so as to close an electric circuit, while, by means of the link 146, the 50 crank arm 145 with the pawl 144 is caused to slide over the teeth of the ratchet wheel 143.

The switch roller 142 is continually in current-conducting connection with a contact 55 pin 153 pressed under the action of a leaf spring 152 against one of its frontal surfaces. On this frontal surface the switch roller 142 is provided with a circular row of shallow holes 154, in which the contact 60 pin 153 snaps successively upon rotation of the switch roller. The holes 154 correspond in their number and position to the teeth of the ratchet wheel 143, so that after each partial rotation of the switch roller 142, the 65 latter will be secured and prevented from

retrograde movement during the idle stroke of the ratchet pawl 144 through the snapping of the contact pin 153 into one of the holes 154.

Against the peripheral surface of the switch roller 142 bears a contact finger 155, which co-operates with the contact pin 153 for closing the circuit. In order that this circuit shall be closed at each second partial rotation of the ratchet roller 142, the peripheral surface of the ratchet roller is divided up into equal sections which are alternately current-conducting and insulated. In the position of the switch roller 142 according to Fig. 2 the contact finger rests against an insulated section 156, so that the circuit is broken. Upon the next partial rotation of the switch roller 142, effected by the spring 150, the contact finger 155 will come to rest on a current-conducting section 157 and consequently produce the circuit closure. The closing of the circuit at D then causes the electro-magnet G to be excited for clearing the coin slot and allowing another coin to be inserted.

The switch lever 148, turned upon the excitation of the electro-magnet L and thereby causing the idle stroke of the ratchet pawl 144 by means of the crank arm 145, is retained in operated position, i. e., with the circuit at D closed, by a detent lever 159 pivoted at 158 and controlled by a spring 161. The lever 148 has a notch 163 wherein one end 162 of the lever 159 is normally accommodated and prevented by the shoulder 164 from moving under the influence of the spring 161. The lever 148, on being operated by the magnet L, frees the lever 159 which is then turned by the spring 161 so as to place the end 162 of the lever under the shoulder 164 and prevent 160 the lever 148 from returning. A link 160 connects the lever 159 with the armature of an electro-magnet K which, on being excited, turns the lever into the normal position and allows the lever 148 to break the circuit at D 165 and to turn the switch roller 142.

The detent lever 159 also co-operates with contacts 165 in a switch E for closing and breaking a circuit, the magnet K effecting the closing and the spring 161 the breaking of the circuit.

A counting mechanism 166 of known type serves for counting the shots fired by means of the rifle. The driving shaft 167 of this mechanism is connected to the switch lever 148 by a crank arm 168 and a link 169 so that each operation of the switch lever by the electro-magnet L moves the counting mechanism to the extent of one member.

Instead of counting the shots, the counting mechanism 166 can serve for counting the coins inserted, in which case the driving shaft 167 preferably receives its drive from the lever 122 which carries the stop 119.

The operation of the apparatus will now

be described with reference to the circuit diagram shown in Fig. 4; it being assumed that an alternating current supply is used for the operation.

5 The projection lamp 87 is connected directly to the high tension current, while the switch mechanism is operated by low tension current over a transformer T.

10 The insertion of a coin is the condition for the use of the automatic shooting machine, such insertion causing a circuit to be closed at A through the contacts 140.

15 Upon loading the rifle by means of the gripping knob 11 on the bolt 13 the lever 24 of the switch B is connected to the contact 30 and occasions the following flow of current. From the transformer T over lead b, c, switch B over contacts 30, lead a, switch A over contacts 140, lead d, electro-magnet L, lead e, switch E over contacts 165, lead f back to the transformer T. Hereby the magnet L is excited and closes the circuit at D over the contacts 151 and opens the circuit at E by the tension of the spring 161.

20 Upon firing the rifle the switch B is changed over to contacts 31 and lead g and causes the following flow of current. From the transformer T over leads b, c, switch B over contacts 31, leads g, h, electro-magnet H, leads i, k, switch D over contacts 151, leads l and f back to the transformer T. Hereby the magnet H is excited and causes the hammer 52 with the perforating needle 51 to mark the target at the striking point. With the operation of the registering device the circuit is 25 closed at C over the contacts 71 by the pin 70 and causes the following flow of current. From the transformer T over leads b, m, switch C over contacts 71 lead n, electro-magnet K, leads o, k, switch D over contacts 151, leads l and f back to the transformer T. Hereby the electro-magnet K is excited, which 30 closes the circuit at E over the contacts 165 and releases the switch lever 148. By means of the tension spring 150 the switch lever 148 is freed from the contacts 151, the counting mechanism 166 is moved to the extent of one number, and the switch roller 142 is rotated 35 so as to make electric contact with the spring 155.

Upon the loading of the rifle necessary for delivery of the next shot the switch B is again changed over through the contacts 30 to the lead a and thereby causes the flow of current already described, which excites the magnet L. Thereby the circuit is closed at D over the contacts 151, and the circuit at E and the contacts 165 is opened.

40 Upon the second firing of the rifle the switch B is again changed over through the contacts 31 to the lead g, and the different circuits are closed and broken in the order already described. However, since the roller 142 is in electric contact with the spring 155 on the firing of the second shot, the change

over of the switch B to contacts 31 causes another circuit to be closed wherein the current flows from the transformer T over leads b, c, switch B over the contacts 31, leads g, p, electro-magnet G, lead q, contact finger 155 70 and contact pin 153 of the switch roller 142, lead r, contacts 151 and leads l and f back to the transformer T. The electro-magnet G therewith opens the circuit at A and at the same time clears the coin slot.

75 A motor 83 for moving the target receives its current over a switch E. When the latter is closed, the motor is switched on automatically over the contacts 151 upon loading the rifle and switched out again upon firing. The flow of current is as follows: From the transformer T over leads b, s, switch F, lead t, motor 83, lead u, i, k, switch D over the contacts 151, leads l and f back to the transformer T.

80 The entire installation can, when not in use, be rendered current-less by means of a master switch J.

85 When the apparatus is operated with direct current, a suitable ohmic resistance is employed in place of the transformer T.

It is obvious that, as compared with the illustrated example, modifications in the construction and in the size of the individual portions of the machine and in the electrical connection, can be adopted according to desire or requirement, without exceeding the scope of the invention.

90 What I do claim as my invention and desire to secure by Letters Patent is:—

1. In an electrically operated, cinematographic shooting machine comprising a target piercing mechanism and rifle with hand operated loading mechanism and trigger, the combination with an operating magnet for said target piercing mechanism, of a switch arranged in the circuit of said operating magnet, a closing magnet for said switch, a coin operated switch in the circuit of said switch closing magnet, and a two-way switch 95 operative to complete the circuit of said switch closing magnet when the loading mechanism is operated and to complete the circuit of said operating magnet on the trigger being pulled.

100 105 110 115 120 125 130

2. The structure claimed in claim 1 in combination with means for retaining the coin operated switch and the magnetically operated switch in closed position, and electro-magnetic means controlled by the trigger for opening said switches.

3. The structure claimed in claim 1 in combination with means for retaining the coin operated switch in closed position, an electro-magnet for opening said latter switch, a rotary switch in the circuit of said latter magnet, and means for imparting partial rotation to said rotary switch at each firing of a shot, said rotary switch operated to close the circuit of said latter magnet after a pre-

determined number of shots having been fired.

4. The structure claimed in claim 1 in combination with a coin chute, a stop lever in said chute, means for forcing a coin past said stop lever so as to rock the same, said stop lever operative, on thus being rocked, to interlock with the coin operated switch and to be retained by the latter in operated position, a blocking lever for the chute controlled by said stop lever so as to be turned into blocking position when the stop lever is

rocked by the coin, an electro-magnet operative to restore the levers to their normal positions, a rotary switch in the circuit of said latter magnet, means for imparting partial rotation to said rotary switch at each firing of a shot, said rotary switch operative to close the circuit of said latter magnet after a predetermined number of shots have been fired. 70

In witness whereof I have hereunto signed my name this 15th day of May, 1930.

FRIEDRICH CLAUS HEINRICH HANSEN.
